UNITED STATES PATENT OFFICE.

FERDINAND BURCHARTZ, OF NEW YORK, N. Y., ASSIGNOR TO BURCHARTZ FIRE-PROOFING COMPANY, INC., A CORPORATION OF NEW YORK.

FLOOR OR CEILING CONSTRUCTION.

1,162,028.

Specification of Letters Patent. Patented Nov. 30, 1915.

Application filed February 10, 1911. Serial No. 607,759.

To all whom it may concern:

Be it known that I, FERDINAND BURCHARTZ, a citizen of the United States, and resident of the borough of Manhattan, city, county, and State of New York, have invented certain new and useful Improvements in Floor or Ceiling Construction, of which the following is a specification.

My invention relates to floor and ceiling construction and has for its object to produce a floor or ceiling composed of individual blocks set up in a certain correlation to each other to form intersecting channels adapted to receive the usual tie rods and material such as cement or the like for binding the blocks into a monolithic structure and for forming reinforced load carrying beams or girders.

A further object of my invention is to provide a hollow block having open ends and provided on one side with a recessed extension for forming the said intersecting channels, the blocks being preferably arranged in pairs with the extensions of one pair of blocks arranged adjacent to and closing the open ends of the next adjacent pairs of blocks. In other words in my improved construction the blocks are positioned in sets of two, the axes of adjacent sets extending at right angles to each other, so that each set of blocks will lie between and close the open ends of two spaced and alining sets of blocks and prevent the cement or other binding material placed between the blocks from reaching the interior thereof.

My invention will be fully described hereinafter and the features of novelty will be pointed out in the appended claims.

Reference is to be had to the accompanying drawings in which—

Figure 1 is a sectional elevation of a portion of my improved floor or ceiling construction; Fig. 2 is a plan view thereof; Figs. 3, 4 and 5 are cross-sectional views illustrating three different forms of my improved block, Fig. 6 is a horizontal section of one block showing a means for closing the one open end of the end blocks in a row and Fig. 7 is a cross section thereof on the line 7—7 of Fig. 6 looking in the direction of the arrow.

My improved block comprises a hollow body portion A having opposite open ends and provided or supplied on one side with

a recessed L-shaped extension a forming a channel b. The extension a is preferably but not necessarily formed integral with the body portion A and extends parallel with the axis thereof. The wall of each body portion A 60 on the side opposite to that on which the recessed extension a is located is preferably inclined as indicated at c in Fig. 1. In constructing a floor or ceiling according to my present invention the blocks are set in pairs 65 on a temporary scaffolding or centering, with the inclined walls c opposed to or adjacent to each other as shown in Fig. 1. Each adjacent set or pair of blocks in each row is positioned with the axes thereof extending at right angles to each other, so that the extensions a of one set of blocks will close the open ends of the two sets of blocks arranged to either side thereof. In other words the blocks in pairs or sets are arranged in parallel adjacent rows, the sets of blocks in each row having their axes extending alternately at substantially right angles to each other, so that the recessed extensions a of each set of blocks serve to close 70 the open ends of the two adjacent sets of blocks and in turn have their open ends closed by the extensions a of the co-operating sets of blocks in the next adjacent rows. 75 With this arrangement which is clearly shown in Fig. 2 of the drawings, the recessed extensions a of each alternate set of blocks aline with each other and form continuous channels b which extend throughout 80 the floor or ceiling and intersect each other. 85 These channels b serve to accommodate the usual reinforcing or tie rods d and are also adapted to receive the cement, concrete or other material e for securing the blocks together in a monolithic structure and which forms intersecting concrete or other load carrying beams or girders. 90

The extensions a in addition to forming the channels b also serve to position the sets of blocks and to properly space them apart so that no particular skill or care is required in constructing the floor or ceiling. The extensions a are further preferably of a length corresponding to the outside width of two body portions, so that each extension a in the finished structure will extend across one open end of two body portions A forming 100 a set. It will be seen that when the blocks are set up as described the opposed ends of adjacent extensions a are spaced 105 110

- from each other and form spaces f as clearly illustrated in Fig. 2. The temporary scaffolding or centering forms a temporary bottom for these openings f so that the material 5 will enter and fill said openings but will not fall through the same and after becoming set will serve as a key or projection to prevent any movement of the blocks A relatively to each other. A very solid and efficient structure is thus secured capable of 10 withstanding heavy strains and yet light in construction so that the dead weight of a floor or ceiling constructed according to my invention is reduced to a minimum. The cement or other material e forming the beams or girders also enters the spaces between opposed walls c of each set of blocks 15 so that no dry joints exist between the blocks in a set in the finished structure.
- 20 It is sometimes very desirable to interrupt the concrete or other material instead of having the same in the form of a complete slab as in Figs. 1 and 2, for which reason I may use the form of blocks shown in Figs. 3, 25 4 and 5. In Fig. 3 the blocks A are provided with integral projections g which extend throughout the length of each block but do not extend throughout the entire width thereof. In Fig. 4 the projections g' 30 are formed by merely thickening the upper wall of the body portions A and in addition are provided with ventilating channels g^2 which extend lengthwise thereof. In Fig. 5 the projections g^3 extend lengthwise of the 35 body portion A and are spaced from each other by a dovetail groove in which a wooden or other sleeper g^4 is secured. This is a very useful and convenient form when it is desired to cover the complete floor or ceiling 40 with a covering of wood or with other material as the said projections g^3 not only interrupt the binder but the said sleepers g^4 provide a ready means in which fastening means such as nails or screws for securing 45 the covering in position may be driven. These last three forms of block are otherwise the same as the form shown in Figs. 1 and 2 and may be set up and used in exactly the same way.
- 50 In instances where the end blocks of a row owing to their relative location are spaced from the walls of the building and have their open ends exposed I provide a U-shaped closure h , the members h' of which 55 extend into the body portion A of the block. In order to prevent this closure from being forced entirely into said body portion I may provide the blocks intended for the ends of a row with ribs or partitions h^2 extending 60 lengthwise of the said body portion. These partitions serve to limit the inward movement of the closure h and to position the same so that the transverse wall thereof is not flush with the block end but projects beyond the same, and is thus locked against

any movement by the cement or other material. This closure h is of a size to completely cover the open ends of the blocks wherever necessary and prevents the material from entering the interior of the 70 bodies A.

While I have shown two ribs or partitions in Figs. 6 and 7 I desire it to be understood that in some cases a single central rib will be sufficient for the purposes intended, or 75 stops of other form may be provided. Furthermore the rib or ribs need not be continuous and extend throughout the length of the body A but may be interrupted at a point within the body portion A.

The various forms of blocks used in my improved floor or ceiling construction are easily and cheaply made and are very light and yet capable of resisting heavy strains and together with the beams or girders 85 formed by the cement, concrete or other material in the channels b results in a structure capable of sustaining heavy loads, the reinforced concrete or other girders themselves acting as load carrying elements in 90 addition to binding the blocks together in a monolithic structure. The said blocks may be made of any suitable material but are preferably made of fireproof material such as clay, concrete, terra cotta or the like. 95

Various changes in the specific forms shown and described may be made within the scope of the claims without departing from the spirit of my invention.

I claim:

1. A floor or ceiling comprising a plurality of open ended blocks arranged with the open ends of one block spaced from the side walls of adjacent blocks, upright members extending across and closing the open ends of said blocks, means for spacing said upright members from the side walls of said blocks whereby channels are formed between adjacent blocks and a coalescent material in said channels.

2. A floor or ceiling comprising a plurality of open ended blocks arranged with the open ends of one block spaced from the side walls of adjacent blocks, angle members extending across and closing the open ends of said blocks and with the side walls of said blocks forming channels between adjacent blocks and a coalescent material in said channels.

3. A floor or ceiling comprising a plurality of open ended blocks arranged with the open ends of one block spaced from the side walls of adjacent blocks, L-shaped members extending along the side walls of said blocks and closing the open ends of adjacent blocks to form channels between adjacent blocks and a coalescent material in said channels.

4. A floor or ceiling comprising a plurality of open ended blocks arranged with the open ends of one block spaced from the

5 side walls of adjacent blocks, upright members extending across and closing the open ends of said blocks, means for spacing said upright members from the side walls of said blocks whereby channels are formed between adjacent blocks, tie rods extending lengthwise of said channels and a coalescent material in said channels.

10 5. A floor or ceiling comprising a plurality of open ended blocks arranged in rows with the open ends of each alternate block in a row spaced from the side wall of an adjacent block in said row, upright members extending across and closing the open ends 15 of said blocks, means for spacing said members from the side walls of said blocks whereby intersecting channels are formed, tie rods extending lengthwise of said channels and intersecting each other and a coalescent material in said channels.

20 6. A floor or ceiling comprising a plurality of open ended blocks arranged in rows with the open ends of each alternate block in a row spaced from the side wall of an adjacent block in said row, L-shaped members extending along the side walls of said blocks and closing the open ends of adjacent blocks to form intersecting channels, the ends of said L-shaped members in each row being 25 spaced from each other and a coalescent material in said channels and in the spaces between the ends of said L-shaped members.

30 7. A floor or ceiling comprising a plurality of open ended blocks each having an inclined side wall, said blocks being arranged in pairs with their inclined side walls opposed to each other to form V-shaped recesses, and having their open ends spaced from the outer side wall of an adjacent 35 block, angle members extending across and closing the open ends of said blocks and forming channels with said outer side walls and a coalescent material in said channels and said V-shaped recesses.

40 45 8. In a floor construction the combination

with a body of concrete, of a tile structure embedded in the concrete comprising a plurality of units composed each of a tubular element open at its ends, L-section elements at its sides with their upstanding flanges 50 spaced away from the tubular element by their horizontal flanges; said units being arranged so that the open ends of the tubular elements of said units are closed by the upstanding flanges of the L-section elements 55 of adjacent units, whereby two sets of intersecting channels for concrete are provided between said tubular elements.

9. In a floor construction the combination with a body of concrete, of a tile structure 60 embedded in the concrete comprising a plurality of units composed each of a tubular element open at its ends, L-section elements at its sides with their upstanding flanges 65 spaced away from the tubular element by their horizontal flanges so as to provide channels for the concrete; said units being arranged so that the open ends of the tubular elements of said units are closed by the sides of adjacent units. 70

10. In a floor construction the combination with a body of concrete, of a tile structure embedded in the concrete comprising a plurality of units composed in each case of a hollow element closed at the top and sides, 75 but open at its ends, L-section elements at its sides with their upstanding flanges spaced away from the hollow element by their horizontal flanges so as to provide channels for the concrete; said units being arranged so 80 that the open ends of the hollow elements of said units are closed by the sides of adjacent units.

85 In testimony whereof, I have hereunto set my hand in the presence of two subscribing witnesses.

FERDINAND BURCHARTZ.
